(57) **CLAIM**

The ornamental design for an agricultural mower unit, as shown and described.

DESCRIPTION

FIG. 1 is an upper, left, rear perspective view of an agricultural mower unit, showing my new design;

FIG. 2 is an upper, left, front perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

The broken lines in the figures depict environmental features that form no part of the claimed design.
